[57] **CLAIM**

The ornamental design for a tool mounting base, as shown.

DESCRIPTION

FIG. 1 is a left side elevational view of a first embodiment of the tool mounting base showing our new design;
FIG. 2 is a front elevational view thereof;
FIG. 3 is a right side elevational view thereof;
FIG. 4 is a rear elevational view thereof;
FIG. 5 is a top plan view thereof; and
FIG. 6 is a bottom plan view thereof;
FIG. 7 is a left side elevational view of another embodiment of the tool mounting base including a clamping attachment;
FIG. 8 is a front elevational view thereof;
FIG. 9 is a right side elevational view thereof;
FIG. 10 is a rear elevational view;
FIG. 11 is a top plan view thereof; and,
FIG. 12 is a bottom plan view thereof.
